UNITED STATES PATENT OFFICE.

ELBERT HAMILTON SEARLE, OF SPRINGFIELD, MASSACHUSETTS.

DESIGN FOR AN AIR-RIFLE.

44,034.

Specification for Design.

Patented May 13, 1913.

Application filed January 29, 1912. Serial No. 674,218. Term of patent 14 years.

To all whom it may concern:

Be it known that I, ELBERT HAMILTON SEARLE, a citizen of the United States, residing at Springfield, in the county of Hampden and State of Massachusetts, have invented a new, original, and ornamental Design for Air-Rifles, of which the following is a specification, reference being had to the accompanying drawing, forming part thereof.

In the drawing, Figures 1, 2 and 3 are respectively a side, a top plan and a bottom plan view of my new design.

I claim:

The ornamental design for an air rifle, as shown.

The foregoing specification signed at Berlin this 8th day of January 1912.

ELBERT HAMILTON SEARLE.

In presence of two witnesses:

WOLDEMAR HAUPT,

HENRY HASPER.
